CAP

Grabel B. Weber, Chicago, Ill., assignor to White Castle System, Inc., Columbus, Ohio, a corporation of Delaware

Application September 29, 1952, Serial No. 21,631

Term of patent 14 years

(Cl. D3—13)

To all whom it may concern:

Be it known that I, Grabel B. Weber, a citizen of the United States, residing at Chicago, in the county of Cook and State of Illinois, have invented a new, original, and ornamental Design for a Cap, of which the following is a specification, reference being had to the accompanying drawing, forming a part thereof.

Fig. 1 is a perspective view of a cap showing my new design;

Fig. 2 is a side elevational view thereof;

Fig. 3 is a top plan view; and

Fig. 4 is a vertical sectional view taken through the cap along the line 4—4 of Fig. 1.

The opposite side of the cap shown in Fig. 2 is similarly ornamented and presents a substantially similar appearance as the side shown.

I claim:

The ornamental design for a cap, substantially as shown and described.

GRABEL B. WEBER.
